QUETCH

William J. Koch, Midland Park, N. J., assignor
to Van Vlaanderen Machine Company, Pater-
son, N. J., a corporation of New Jersey

Application September 24, 1931
Serial No. 564,834

5 Claims. (Cl. 91—51)

This invention relates to apparatus, known as a quetch, in which fabric or other porous sheet material is treated with sizing liquid, or size, by pressing it between two revolving rolls, 5 one of which has the size applied to it, usually by dipping into a body of size in a suitable container. When the "lacing" or entering of the fabric between the rolls is effected they are usually separated. My invention contemplates 10 in part an improvement whereby this and also the desired pressure exerted by one roll toward the other when they are compressing and sizing the cloth are accomplished. When separation of the rolls is effected it is desirable in any 15 event, but especially if the rotation of the rolls is also stopped, to discontinue the dipping of the roll which transfers the size to the fabric. Wherefore my invention further contemplates constructing the mechanism so that the act of 20 separating the rolls shall result in removing the size-applying means from the size-transfer roll. It is found that the motion of a roll which dips into the size causes the latter to foam and that this foam spills from the container and pro- 25 duces an untidy condition about the machine and that this foam, with scum, forms as a top layer on the size and is not only likely to reach the cloth and cause spotting or staining thereof but that it conceals the size so that the actual 30 level of the size and hence its quantity is not apparent, with the possibility that the machine may be operated without size and the fabric injured or required to be re-treated in the machine. The invention therefore further con- 35 templates constructing the machine so that the foam as fast as it is formed is directed away and permanently isolated from the main body of the size.

In the drawings,

40 Fig. 1 is a side elevation of the improved quetch;

Fig. 2 shows the size container in longitudinal section, with the lower roll (in outline) dipping into the size;

45 Fig. 3 is a section on line 3—3, Fig. 2; and

Fig. 4 shows in front elevation a detail of Fig. 1.

In the frame 1 are the coactive cloth-pressing elements comprising the lower pressure roll 2 and two levers 3 fulcrumed in the frame and the upper pressure roll 4 journaled in such levers; the lower pressure element 2 is journaled in the frame in fixed bearings and the upper pressure element 3—4 rests thereon as shown, though being 55 adapted to be elevated clear thereof to separate the rolls. At 5 is a suitably driven drive shaft having a worm 6 meshing with a worm-wheel 7 having a gear 8 meshing with a gear 9 on roll 2, which when roll 4 is depressed drives the latter by 60 friction. The cloth is unwound from a freely

revoluble beam 10 and is wound up on the receiving beam 11 driven through an endless belt-and-pulley connection 12 from roll 2. So much is well known.

In the frame below the rolls is what I term a 65 load structure movable up and down and here comprising two opposed levers 13 fulcrumed at 13a in the frame and carrying weighting means 14 and forming the body member of such structure, which latter also comprises two opposed cranks 16 having pivots 16a and oscillatory in the body member around a horizontal axis, as that of shaft 15 to which the cranks are affixed and which is here journaled in the levers and also forms a part of the load structure. A pair 70 of opposed links 17 are connected to the pivots 3a to articulate thereon and depend therefrom, being also connected to the pivots 16a to articulate thereon. At 18 is a stop on which the load structure may come to rest, i. e., when the pressure element 3—4 is elevated. When the cranks are turned anti-clockwise to the position shown the upper pressure element is first allowed to fall to rest on the lower one and then, this movement being continued, the cranks now cause the load 75 structure of which they form a part to rise, thus imposing the weight of the load structure on the upper pressure element, such movement also resulting in pivot 16a passing (under shaft 15) beyond a straight line connecting pivot 3a and the 80 axis of the cranks, and the links coming to abut the load structure, as against its shaft 15, thus leaving the parts releasably locked in this state. When the cranks are turned back, and during 85 their ensuing half-revolution, the motion results in the links first permitting the load structure to fall and abut stop 18 and then elevating the upper pressure element clear of the lower one, pivot 16a again passing the mentioned line and the 90 links again abutting the load structure (at 15) and leaving the parts again releasably locked in their new position. Whereas this mechanism is 95 not broadly new, it is new to embody the crank or cranks as actually a part of the load structure, which considerably simplifies the construction, avoids undesirable lost-motion and increases the efficiency of the mechanism.

Shaft 15 may be rotated by any suitable means. But for a purpose to appear I propose to obtain its motion from a rotary shaft 19 located more or less near the lower pressure roll 2. This shaft has a crank-like handle 20 and it and shaft 15 are connected to rotate together back and forth by an endless chain 21 engaging sprocket-wheels 22, 23 on these shafts.

The size pan or container 24 (which may be charged through a funnel 29) has depending side legs 24a each slotted to receive and thus be guided for vertical movability by shaft 19 and a stud 25 on the frame, and it also has at each side 115 120

a roller 26 which, by resting on an eccentric cam 27 on the shaft, supports this container. Each cam is so positioned on the shaft that when through the links the load structure is holding roll 4 pressed against roll 2 the container is elevated so that the latter roll dips into the size in the container; and when the load structure rests at 18 and the links are holding roll 4 elevated the container will have descended to clear the size 10 from roll 2. Thus, whenever for any purpose, roll 4 being elevated, the intended sizing operation (to wit, with compression of the cloth) is not going on, the size will then be removed from roll 2 so that the latter will not become gummed or 15 unduly coated with the size.

So far as I am aware it is broadly new to provide in machines of this class, in combination, a revoluble pressure roll and another revoluble pressure roll movable into and out of pressure 20 relation to the first roll, a size-applying means (as the container) movable into and out of size-applying relation to one of such rolls, and mechanism (here, by way of example, parts 3, 17, the load structure, the cam and the sprocket-and- 25 chain connection between the cam and the crank-carrying shaft 15 of the load structure) controlling said movable roll and means and movable to establish them simultaneously in or simultaneously out of the positions where the 30 former presses against the other roll and the latter applies size to one of such rolls.

Again, given a machine of this class having a revoluble pressure roll, back-and-forth-movable means (as the levers 3, links and load structure) including a revoluble pressure roll (as 4) and movable in one direction to cause its roll to exert pressure on the first roll and in the opposite direction to relieve such pressure, and size-applying means movable back and forth into and out 35 of size-applying relation to one such roll, it is new to provide means (as the cam and sprocket-and-chain connection) to move back and forth the first two means in synchrony.

It is also new, given a machine having said 45 pressure roll and said back-and-forth-movable means and back-and-forth-movable size-applying means, to provide toggle-including means (the toggle being here afforded by the links and cranks) to move the first two means back and forth in synchrony and when they are at one of their limits of motion releasably lock them 50 against return.

Container 24 is divided by an upstanding barrier 28, removed from the uptake (here the right) 55 side of roll 2, the compartment at the left thereof (into which roll 2 depends) containing the size, whose level is maintained slightly below the top of the barrier, and the compartment at the right forming a drain and having for this purpose its bottom sloping toward the outlet 30 provided with a stop-cock 31. The rotation of the roll in the size causes, as stated, undesired foaming thereof, but when the container is constructed as thus described this foam is impelled by roll 2 60 as fast as it is formed over the barrier and escapes by the drain so that the mentioned disadvantages attending the presence of the foam when it is allowed to accumulate on the size are avoided. Of course the remaining upstanding portion of the container which coacts with the barrier to confine the size-liquid reaches higher 65 than the barrier so that the foam may not escape except over the barrier.

Having thus fully described my invention, what I claim is:

1. A machine of the class described comprising supporting means, superposed pressure elements therein one of which is movable up and down and normally bears against the other and has a pivot, a link connected with and depending from said pivot, an up-and-down-movable load structure comprising a body member and a crank oscillatory in the latter around a horizontal axis and having a pivot to which the lower end of the link is connected, said means having a stop to limit the downward movement of said structure, and said link, when the crank is turned in one direction until its pivot passes a straight line between 80 said axis and the first pivot, being adapted to abut the load structure and then suspend the latter from the first pressure element and elevated above the stop, and, when the crank is turned back and during the ensuing half-revolution thereof, being adapted to first permit the load structure to fall and abut the stop and then move the first from the other pressure element. 85

2. A quetch comprising a frame, a revoluble 100 pressure roll arranged in the frame, another pressure roll movable in the frame into and out of pressure relation to the first roll, a size-applying means movable in the frame into and out of size-applying relation to one such roll, and mechanism 105 controlling said movable roll and means and movable to establish them simultaneously in or simultaneously out of the positions where the former presses against the other roll and the latter applies size to one roll. 110

3. A quetch comprising a frame, a lower revoluble pressure roll, a pressure element including an upper revoluble pressure roll and movable up and down respectively to shift such roll from and into pressure relation to the lower roll, a size-applying means under the lower roll and movable up and down respectively into and out of size-applying relation to said lower roll, and mechanism 115 controlling said element and means and movable to establish them simultaneously in or simultaneously out of the positions where the upper roll presses against the lower roll and said means applies size to the lower roll.

4. A quetch comprising a frame, a revoluble 125 pressure roll arranged in the frame, back-and-forth-movable means including a revoluble pressure roll and movable in the frame in one direction to cause such roll to exert pressure on the first roll and in the opposite direction to relieve such pressure, size-applying means movable in the frame back and forth into and out of size-applying relation to one such roll, and rotary means to move the first two means back and forth in synchrony. 130

5. A quetch comprising a frame, a revoluble 135 pressure roll arranged in the frame, back-and-forth-movable means including a revoluble pressure roll and movable in the frame in one direction to cause such roll to exert pressure on the first roll and in the opposite direction to relieve such pressure, size-applying means movable in the frame back and forth into and out of size-applying relation to one such roll, and toggle-including means to move the first two means back and forth in synchrony and when they are at 140 one of their limits of motion releasably lock them against return. 145

WILLIAM J. KOCH.
